UNITED STATES PATENT OFFICE.

JOSEPH PERCY REMINGTON, OF PHILADELPHIA, PENNSYLVANIA.

PROCESS OF BEACH-BUILDING.

1,274,450.

Specification of Letters Patent.

Patented Aug. 6, 1918.

Application filed May 20, 1916. Serial No. 98,730.

To all whom it may concern:

Be it known that I, JOSEPH PERCY REMINGTON, residing at Philadelphia, in the county of Philadelphia and State of Pennsylvania,

5 have invented a new and useful Process of Beach-Building, whereof the following is a specification, reference being had to the accompanying drawings.

The invention relates to a process of beach building in which the power of the waves themselves is utilized for the purpose, and more particularly to a method and means whereby the destructive and erosive forces of the waves and tides are checked and separated from the constructive forces which are thereby enabled to carry on their normal work of accumulating and piling up sand without this work being immediately undone.

20 The changes and alterations in any beach due to the action of the waves depend entirely on the ratio between the amount of sand which is carried in and deposited by each incoming wave, and the amount which 25 is carried out by the succeeding ebb. The relative strength of these two actions will determine whether the beach builds up or wears away. Each wave or breaker as it approaches the beach, carries with it a certain amount of sand, which though drawn up from the bottom is carried in suspension throughout the whole wave. When the wave is dissipated on the beach, the suspended sand is precipitated and will remain on the 30 beach, unless carried out by the ebb. The receding flow, however, may collect this sand which has just been deposited and may draw out with it other sand from the surface of the beach. But all the sand carried thereby, 35 having just been drawn from the beach, remains for some time in the lower layer of the receding flow, which is not normally more than an inch or so in thickness.

If the lower outgoing layer travels very 45 rapidly or encounters another incoming flow, so that the sand carried thereby is stirred up through the whole wave, precipitation is prevented and the beach wears away but if this layer travels at a comparatively slow rate of 50 speed, and does not encounter any incoming flow, then precipitation is permitted, and the beach builds up.

This process is going on all the time, and is the same in storms as in calms, but much 55 more rapid in its operation in storms, because of the increase in both forces, and the

fact that side currents may cause the incoming and outgoing waves to travel different courses, thereby bringing the sand in at one place and carrying it out at another.

60

Attempts have been made heretofore to prevent the wearing away of the beach by means of jetties thrown out into the water at right angle to the shore line, or bulkheads parallel to the shore line, but these have 65 never been more than partially successful. It is true that jetties will prevent a strong current running parallel to the shore from setting in so close as to eat it away; but they will not affect the changes due to the normal 70 action of the waves coming directly in. Bulkheads on the other hand will not prevent a side current from setting in, and merely oppose their force to that of the waves. As a result each wave is turned back 75 on the next succeeding one, so that when they meet the sand is so stirred up that it has no chance to precipitate. In addition to this eddies and side currents are formed which have a scouring effect on the beach, 80 and carry away vast quantities of sand. This is especially true during storms. Both of these methods are, however, attempts to oppose the normal action of the waves.

It is the object of my invention to check 85 the erosive forces of the waves without opposing the constructive forces and to so regulate these forces that the relation between them is always in favor of the constructive forces, so that continual building of the 90 beach results. In accomplishing the object advantage is taken of the fact that sand is carried by the incoming and outgoing waves at different levels, as described. I, therefore, provide means for preventing separating the action of the incoming and outgoing flows, and the outward passage of the sand in a manner which does affect its inward 95 passage.

To this end I place a builder consisting of 100 a low and substantially water-tight retaining wall at some point on the beach where the waves can flow over it, provided with one or more V shaped pockets, in a line substantially parallel to the line of the shore. 105 The wall is low enough and is so placed that the landward flow during at least part of each tidal period will be able to pass over and beyond it without being materially impeded. But on the other hand it must be 110 high enough to hold back the undertow, or lower strata of each succeeding seaward

flow. As has been explained, nearly all of the sand carried by the receding seaward flow is carried in this lower layer, and by checking the speed of this lower layer at the 5 same place each time, the sand carried by it will be given a chance to precipitate and deposit at that place, while the clear water will flow off over the top of the barrier. In this manner the erosive wash is prevented or at 10 least decreased, while the amount of sand which is brought in by each wave is not substantially decreased, for being carried in suspension throughout all parts of the wave, it is brought in over the top of the barrier 15 without hindrance. This is rendered possible by the V shaped construction of the pockets for as the incoming wave-front encounters the wall, it is broken up by the seaward points of the wall, and deflected into 20 a number of different channels. The narrowing walls of the V shaped pockets have the effect of constricting the wave front and increasing the speed of the waves so that they are given power enough to carry the 25 sand over the retaining wall at the landward points of the pockets. The seaward flow, on the other hand, is divided by the landward points of the wall and deflected into the pockets on the other side, and caused to flow 30 off over the seaward apices. In this way the lower layer of the seaward flow is checked and caused to pass back over the wall at different points from that at which the incoming flow passes over it. As a result 35 the two forces do not encounter each other, and there is no stirring up of the sand carried by the seaward flow which would prevent precipitation.

As a result of this process the sand from 40 each outgoing wave is precipitated in one of the V shaped pockets and is collected there until the pocket gradually becomes filled up. At the same time any back wash or scouring action is prevented in front of the retaining 45 wall and a dead water space provided instead. This dead water space allows the deep water sand to precipitate and settle on the seaward side of the jetty, from whence it is later forced landward over the barrier. 50 In this way the beach builds up in front of the wall as well as in back of it. By then increasing the height of the builder, the process may be repeated and more sand collected until the new height is reached. By 55 increasing the height of the wall each time that the pockets become filled up, the height of the beach may be increased until finally it reaches a point where the waves will no longer flow over it, and consequently no 60 more sand can be deposited.

After this point has been reached, the beach may be further built up and extended by the erection of new builders on the seaward side of the first, and increasing their 65 height as they fill up, until the limit is

reached. In this way by the addition of successive builders on the seaward side the beach may be gradually extended.

It may sometimes be found convenient to take out the old builders and use them over again in a more advanced position, or to have two or more of the builders in operation at once, but this will of course depend on circumstances and the nature of the beach. But in all cases in order to have the builder 75 operate successfully, the walls must be low enough to allow the waves to flow over them, at least at the landward apices, for the entire amount of sand which can be collected will depend on the amount which is brought over 80 the barrier by the incoming waves.

I will now describe appropriate construction by which I may carry out my process.

Referring to the accompanying drawings, Figure I, is a plan view of a beach, showing 85 the application of a convenient form of beach builder employed in carrying out my invention.

Fig. II, is a sectional elevation taken on line II—II in Fig. I.

Figs. III and IV, are detail sectional views on a somewhat larger scale showing the successive stages of beach building as practised according to my invention.

The builder consists broadly of a low and 95 substantially water-tight retaining wall 1, constructed preferably in a substantially zig-zag line running parallel to the beach and providing landward pockets 2, and seaward pockets 3. Owing to the natural slope 100 of the beach the seaward pockets 3, are shallowest at their apices 5, and the landward pockets 2, are deepest at their apices 4. As a result, the landward flow is deflected by 105 the apices 4, into the pockets 3, and caused to pass over the walls near the shallow part at the apices 5. The receding seaward flow is deflected by the apices 5, and into the pockets 2, so that it is caused to pass back over the barrier at apices 4, at which points 110 the top of the wall is highest from the beach. In this way the seaward flow is checked by the wall 1, and forms pools in pockets 2 in which the sand precipitates while the clear water flows off over the top.

The builder may be of any convenient construction or material. In the embodiment shown in the drawings I have employed boards 10, set in the sand to a depth sufficient to prevent leakage and set at right 120 angles to each other so as to form a zig-zag line. These boards are built up above the level of the beach to a height sufficient to enable them to exercise a retarding action on the receding flow. In order to support boards 10, and hold them properly in place, piles 11, are driven on opposite sides of the boards. These piles are driven deep enough to provide the requisite strength and support for boards 10, but should ex- 125 130

tend a sufficient height above the level of the beach to enable them to support other boards which may be subsequently placed on top of the original wall as the pockets 5 fill up with sand.

At either end of the builder a wing wall 6, may be run back beyond high water mark, at any desired angle, or the end may be connected with a spur jetty 7. Similar walls or 10 spurs may be run back as often as desired from any one of the landward apices 5, to prevent the scouring of the beach by coast-wise currents.

Obviously, the carrying out of my process 15 is not limited to any one structure, but the builder may be varied as to material, height, shape or form, as circumstances will admit, but it is necessary that some sort of pocket or pockets be formed which do not 20 oppose the front of the landward flow, but constrict it and enable it to pass over the top of the barrier, but are capable of retarding the lower layer of a seaward flow.

Referring more particularly to Figs. III 25 and IV, Fig. III, represents a builder when first placed on the beach. It is placed slightly above the lower water line 15, and the top board 12, is arranged to be slightly below the high water line 16. In this way 30 some of the waves with each tide are compelled to flow over it, carrying sand which will be deposited and caught by the builder. The piles 11, however, project up to the line 17, of the storm tide, above which the waves 35 never come, and above which any builder barrier would be useless.

Fig. IV, shows the builder after it has been in operation for some time, and has been filled to its capacity, building up the 40 beach to its storm level by the addition of other boards above the board 12, which was originally the top but which is now quite buried. A second builder 18, similar to the first has been erected at a point on the seaward side of the first builder by which the 45 process is repeated.

Having thus described my invention, I claim:

1. The process of beach building which 50 consists in separating the landward flow caused by the waves from the seaward flow and causing each seaward flow to pass over a barrier, whereby it is sufficiently checked to permit precipitation of the sand carried 55 by it.

2. The process of beach building which consists in causing each landward flow caused by the waves to pass over a barrier at certain points, dividing each seaward 60 flow at said points, and causing it to pass back over said barrier at certain other points, whereby it is checked sufficiently to permit precipitation of the sand carried by it.

65 3. The process of beach building which

consists in constricting a portion of each landward flow caused by the waves, whereby it is given power enough to carry sand with it over a barrier at a certain point and dividing each seaward flow at said points, 70 whereby it is caused to pass back over said barrier at certain other points, where it is checked sufficiently to permit precipitation of the sand carried thereby.

4. The process of beach building, which 75 consists in providing on a beach within tidal limits a three-sided inclosure, capable of retaining sand, and causing the landward flow occasioned by the waves to be deflected and constricted toward one or more points along 80 the front of said inclosure, whereby at said point or points the flow is given power enough to carry sand with it over the front of the inclosure, and checking each receding flow sufficiently to permit precipitation of 85 the sand carried thereby.

5. In a beach builder, the combination of substantially water-tight means for constricting a portion of each landward flow toward a certain point whereby it is given 90 sufficient power to carry sand with it over a barrier at that point, means for deflecting each seaward flow away from that point to points where no landward flow is encountered, and means for checking the seaward 95 flow at said points sufficiently to permit precipitation of the sand carried thereby.

6. A continuous zigzag and substantially 100 water-tight retaining wall located on a beach subject to wave erosion, and extending above said beach a sufficient height to direct the landward flow to certain points and the seaward flow to certain other points.

7. A continuous zigzag and substantially 105 water-tight retaining wall located on a beach subject to wave erosion, said wall having a continuously level top extending above the beach to such a height that each landward flow is divided by the seaward points, and caused to pass over the wall at the landward points, while the seaward flow is divided by the landward points, and caused to pass back over the wall at the seaward points.

8. A continuous zigzag and substantially 115 water-tight retaining wall located on a beach subject to wave erosion in such a position as to provide seaward pockets and landward pockets, together with side walls extending back from said zigzag wall toward the land to a point beyond the high water mark.

9. A substantially water-tight retaining 125 wall located on a beach subject to wave erosion at a point within the tidal limits, said wall having a V shaped pocket with its apex toward the land, whereby a portion of the seaward flow is constricted between the sides of the pocket and caused to flow over the wall at the apex of the pocket, while the 130

seaward flow is divided by said apex and caused to flow back over the wall at other points.

10. A three-sided and substantially water-tight inclosure capable of retaining sand located on a beach subject to wave erosion within the tidal limits, said inclosure having a zigzag wall substantially parallel to the shore line, and side walls running back from said zigzag wall to a point above the high water mark.

11. A three-sided and substantially water-tight inclosure capable of retaining sand

located on a beach subject to wave erosion within the tidal limits, said inclosure having a plurality of seaward points, whereby each incoming flow is divided and caused to flow over the wall intermediate said points.

In testimony whereof, I have hereunto signed my name at Philadelphia, Pennsylvania, this seventeenth day of May 1915.

JOSEPH PERCY REMINGTON.
